UNITED STATES PATENT OFFICE.

GEORGE J. CARLISLE, OF CHICAGO, ILLINOIS.

SOUND-TRANSMITTING APPLIANCE.

1,356,599.

Specification of Letters Patent.

Patented Oct. 26, 1920.

Application filed August 6, 1919. Serial No. 315,606.

To all whom it may concern:

Be it known that I, GEORGE J. CARLISLE, a citizen of the United States, residing at Chicago, in the county of Cook and State 5 of Illinois, have invented certain new and useful Improvements in Sound-Transmitting Appliances, of which the following is a specification.

My invention relates to improvements and 10 features of novelty and structural and functional advantages in sound recording and reproducing appliances, such for example, as phonographs, dictaphones, etc. When employed with sound reproduction devices 15 its main object is the provision of an apparatus of this character which will faithfully present the recorded sound from a record with adequate volume, true tone values, delicate shadings of expression, and 20 without rasping or scratching intrusions which are fully suppressed or muted. A further object or purpose of the invention is the production of an appliance of this type which will reproduce sound accurately and 25 with proper amplification and volume from all styles of phonograph records, both lateral and vertical cut. An additional salient feature of the invention is improved and novel means for modulating or changing the 30 volume or intensity of the sound without interfering with its character or modifying its quality or timbre. To the accomplishment of these and other desirable objects 35 various coöperative structural features are incorporated in the sound-box, in the diaphragm and its mounting, and in the stylus device for transmitting the vibrations to the diaphragm.

In order that those skilled in this art may 40 have a full and complete understanding of the invention and its various advantages I have illustrated in the accompanying drawings, forming a part of this specification, a preferred and desirable embodiment of the 45 same, like reference characters referring to the same parts throughout the various views.

In this drawing:

Figure 1 is an elevation of the improved 50 appliance;

Fig. 2 is a section on line 2—2 of Fig. 1;

Fig. 3 is a bottom face view of the structure showing the mounting of the needle or stylus;

Fig. 4 shows the structure with one portion of the casing or shell removed, illus-

trating the construction of the embossed or ribbed diaphragm more clearly;

Fig. 5 is a face view of the slide for controlling the opening and closing of the apertures in the diaphragm casing or sound-box;

Fig. 6 is an enlarged fragmentary detail section, illustrating the internal cavities in the sound-box, the diaphragm, and its 65 gaskets;

Fig. 7 is an enlarged section of the mounting for the vibratory or rock plate carrying the stylus; and

Fig. 8 is a perspective view of the adjusting mechanism for one of the fulcrums.

Referring to the drawings it will be perceived that the embodiment of the invention shown therein comprises a sound-box or diaphragm shell or casing including two 75 parts 10 and 11 held together or in assembled relation by any approved means, such as one or more screws. The part 10 of this hollow shell has a central aperture 12 communicating with a tone-arm or sound-transmitting tube 13 of the usual type, a portion only of which is shown in the drawings. Around the outer side portion of such member 10 I provide a plurality of enlargements or bosses 14 (in the present instance 80 six) which inside of the shell or casing supply corresponding spaced recesses or cavities 15. The companion shell-member 11 is similarly equipped with an equal number of outstanding projections 16 forming 85 internal cavities 17 in register with the recesses 15.

The thin disk diaphragm 18, desirably of metal, spring brass for instance, coated with a relatively soft material such as beeswax 95 to eliminate any metallic sound, is preferably provided with a series of integral hollow ribs 19 struck up or embossed out of the body of the sheet of metal and radiating from the center thereof to somewhat stiffen such central portion of the vibratory diaphragm to enable the sound-transmitting member 20 connected to its center in the usual way to act over a greater middle area of the diaphragm rather than 100 merely at its geometric center only.

The flat peripheral or circular unribbed or unembossed margin of the diaphragm is held between the two coöperating companion parts of the sound-box or shell between 110 a pair of circular gaskets 21 and 22, desirably small rubber tubes 23 equipped in-

ternally with stiffening wires 24 located in their bores. In the shell or casing member 10 the holding gasket 21 rests on a circular shoulder 25 interrupted, of course, at the 5 cavities or depressions 15, the stiffened or reinforced gasket bridging such gaps and acting as a support for the corresponding parts of the diaphragm at those points. In similar manner the opposite gasket 22 rests 10 on a circular shoulder 26 of the outer shell member spanning the recesses 17 and supporting such otherwise unsupported parts of the vibratory diaphragm.

From this construction it should be clear 15 that the air vibrations or pulsations from both sides of the diaphragm are transmitted to the tone-arm, those from the near side being directly communicated to the tone-arm, and those from the far side of the diaphragm being transmitted thereto around the edge of the diaphragm by reason of the passages provided by the registering cavities or recesses. Such a construction permits of ample volume and intensity of sound 20 and a freedom of movement of the properly supported diaphragm, hence making possible a desirable natural reproduction of the original sounds.

As a means of modulating or varying the 30 sound volume or power and the freedom of vibration of the diaphragm, I provide the casing-member 11 with a series of holes 39 therethrough, preferably one opposite each of the chambers or compartments 17, and 35 inside of the shell and coacting with such apertures I employ a suitably-mounted slide-plate 31 equipped with holes 32 adapted by adjustment of the position of the plate to be brought more or less into register with 40 the casing apertures 39. This slide plate is fitted with a knob or handle 33 projecting outwardly through a slot 34 in the wall 11 by means of which the two sets of holes may be shifted into complete or partial 45 register or into a position wholly out of alignment.

I do not attempt at the present time to state the exact scientific principles and theories of operation of these ribbed or em- 50 bossed diaphragms, recesses, and apertures. I simply know that they operate to materially improve the quality and volume of the reproduced sounds. It is possible that these cavities or compartments act also as 55 resonant chambers with advantageous functions.

The diaphragm arm 20 in the form of a flat bowed metal spring is fixedly secured at its lower end to a vibratory or rocking disk or plate 40 which on its under or opposite face carries the needle or stylus socket 41. The upper end of the spring 20 is fixed between the housing members 10 and 11. As a fulcrum support for the rocking disk or 60 plate I employ a fixed fulcrum point 42

outstanding from the flat edge surface 43 of the casing-element 10. The corresponding face of the rockable disk is recessed at 44 for the accommodation of the point of the member 42, the depression extending 70 approximately one-half way through the thickness of the disk. The other fulcrum member 45 for the disk is mounted on an oscillatorily adjustable arm 46 adapted to turn on a screw 47 threaded into an upper 75 tura 48 in the body 10. This screw extends through a somewhat larger central hole 49 in the disk or plate 40 and also through a central hole of a flat spring disk 50 against which the head 51 of the screw bears. Such 80 relatively-flat spring disk bears around its circular periphery or border on a round collar 52 equipped with a pair of oppositely-disposed pointed tongues or feet 53, 54 engaging recesses in the face of the disk 55 49 which extend approximately half way through its thickness. By this construction the resiliency of the spring disk is employed to evenly press the circular plate or rockable member 40 against the two ful- 85 crum points 42 and 45. Such pressure is subject to control by turning of the holding screw as will be readily understood.

The adjustable fulcrum-bearing arm 46 is fitted with a screw 54 extended through 90 a threaded aperture therethrough bearing at its end on the surface 43 thus normally holding the fulcrum point 45 in proper operative relation with, that is bearing on the face of the circular disk or vibratory plate 40, the fulcrum point being of proper length for this purpose. When, however, it is desired to modify or shift the position of the fulcrum pin 45 and thus vary the ful- 95 crum line of the disk 40, the screw 54 is loosened and the arm 46 moved to the new position and again tightened by the screw. To prevent dislodgment of the plate or disk 40 during such adjustment, the member 10 is provided with a fixed supporting 100 pin 55 the end of which by engagement with a groove 56 in the adjacent face of the disk 40 prevents rotation or displacement of the disk during the adjustment of arm 46.

Under normal conditions the four ele- 105 ments 49, 53, and 45 are in a substantially straight line as shown in dotted line 110 in Fig. 3 and owing to the fact that the needle or stylus socket is remote from such fulcrum line or turning axis the appliance will 115 co-operate with either style of record, that is, a lateral cut record or a vertical or so-called hill-and-valley cut record. When a lateral record is employed the intensity or volume of the transmitted sound may be varied by 120 shifting the position of the arm 46 and its fulcrum point 45, thereby varying the dis- 125 tance between the stylus socket 41 and the turning axis or fulcrum line 42—45. The 130 intensity or volume of sound transmitted

to the tone-arm regardless of the type of record used may be varied by shifting the position of plate 31 so as to open or close more or less the apertures 32 in the dia-

phragm element 11.

Thus the recesses and cavities of the sound-box, the embossed or stiffened metal diaphragm, the spring stylus or diaphragm bar, the coating of the diaphragm, the 10 apertures in the casing surrounding the diaphragm and the mounting of the stylus all co-operate and interact to reproduce the recorded sound with fidelity, suitable volume and adjustable intensity. It will be obvious 15 served that the vibrations are imposed end-wise on the spring 20 which transmits them sideways or at right angles thereto to the diaphragm.

Whereas, in this application and the accompanying drawing, a single simple embodiment of the invention has been presented it will be understood by those skilled in this art that the invention is not limited and restricted to such embodiment but is capable 25 of incorporation in appliances of this general type but of radically different structural features. Stated somewhat differently the invention is not restricted to the precise and exact features of construction presented 30 because these may be changed within comparatively wide limits without departure from the substance of the invention and without the sacrifice of any of its substantial benefits and advantages.

35 I claim:

1. In a sound-transmitting appliance of the character described, the combination of a shell constituting a sound-box having a plurality of internal cavities, and a vibratory diaphragm mounted in said shell, substantially as described.

2. In a sound-transmitting appliance of the character described, the combination of a shell constituting a sound-box, and a vibratory diaphragm mounted in said shell, the latter having a plurality of internal cavities on both sides of the diaphragm, substantially as described.

3. In a sound-transmitting appliance of the character described, the combination of a shell constituting a sound-box, and a vibratory diaphragm mounted in said shell, the latter having a plurality of internal cavities located to afford passages around the edge of the diaphragm, substantially as described.

4. In a phonograph, the combination of a shell constituting a sound-box, a tone-arm connected to said shell, a vibratory diaphragm mounted in said shell, the latter having a plurality of internal cavities located to afford passages around the edge of the diaphragm, whereby the air pulsations from both sides of the diaphragm are transmitted to said tone-arm, and means connect-

ed to said diaphragm adapted to coact with a sound record, substantially as described.

5. In a sound-transmitting appliance of the character described, the combination of a shell constituting a sound-box, a vibratory 70 diaphragm mounted in said shell, the latter having a plurality of internal cavities adjacent to the edge of the diaphragm, and a gasket between said shell and diaphragm against which the latter bears, the gasket 75 bridging said cavities, substantially as described.

6. In a sound-transmitting appliance of the character described, the combination of a shell constituting a sound-box, a vibratory 80 diaphragm mounted in said shell, the latter having a plurality of internal cavities adjacent to the edge of the diaphragm, a gasket between said shell and diaphragm against which the latter bears, the gasket 85 bridging said cavities and comprising a resilient tube with a stiffening wire through its bore, substantially as described.

7. In a sound-transmitting appliance of the character described, the combination of a shell constituting a sound-box, a vibratory diaphragm mounted in the shell, the latter having a plurality of internal cavities located to afford passages around the edge 90 of the diaphragm, gaskets on opposite sides 95 of the diaphragm between the latter and the shell, said gaskets bridging said cavities and being formed of resilient material through the bores of which extend reinforcing or stiffening wires, substantially as described. 100

8. In a sound-transmitting appliance of the character described, the combination of a shell constituting a sound-box having a plurality of internal cavities, and a vibratory diaphragm mounted in said shell, the latter having one or more apertures through 105 its wall leading directly to the outer air, substantially as described.

9. In a sound-transmitting appliance of the character described, the combination of a shell constituting a sound-box having a plurality of internal cavities, a vibratory diaphragm mounted in said shell, the latter having one or more apertures through its wall leading directly to the outer air, and 110 adjustable means governing the extent of opening of the aperture or apertures, substantially as described. 115

10. In a phonograph of the character described, the combination of a shell constituting a sound-box having a plurality of internal cavities, a vibratory diaphragm mounted in said shell, a tone-arm connected to said shell on one side of said diaphragm, the shell having one or more apertures to the 120 atmosphere through its wall on the opposite side of the diaphragm, and means to vary the extent of opening of the aperture or apertures, substantially as described. 125

11. In a phonograph of the character de- 130

scribed, the combination of a shell constituting a sound-box, a vibratory diaphragm mounted in said shell, a tone-arm connected to said shell on one side of said diaphragm, the shell having a plurality of internal cavities located to afford passages around the edge of the diaphragm and one or more openings to the atmosphere through its wall on the side of the diaphragm opposite said tone arm, substantially as described.

12. In a phonograph of the character described, the combination of a shell constituting a sound-box, a vibratory diaphragm mounted in said shell, a tone-arm connected to said shell on one side of said diaphragm, the shell having a plurality of internal cavities located to afford passages around the edge of the diaphragm and one or more openings to the atmosphere through its wall

on the side of the diaphragm opposite said tone arm, and means to vary the extent of opening of said aperture or apertures, substantially as described.

13. A sound-transmitting appliance including in combination a vibratory diaphragm, a vibration-transmitting leaf spring bearing between its ends on said diaphragm, and means to impart sound vibrations endwise to said spring, substantially as described.

14. A sound-transmitting appliance including in combination a vibratory diaphragm, a bowed vibration transmitting leaf spring bearing between its ends on said diaphragm, and means to impart sound vibrations endwise to said spring, substantially as described.

GEORGE J. CARLISLE.
